UNITED STATES PATENT OFFICE

VICTOR J. HULTQUIST, OF ALCOA, TENNESSEE

TITLE EDGE FORMING APPARATUS

Application filed March 20, 1931. Serial No. 524,191.

This invention is directed to an improvement in tile edge forming machines, wherein certain edges of the tile may be shaped and formed to meet any desired or special requirements.

In an application filed by me in the United States Patent Office October 20, 1930, Serial #490,025 which has become Patent 1,832,397, I have described and claimed a tile with respective edges adapted for nailing and formed for interlocking with adjacent tile, to thereby provide for accurate and correct tile laying without necessitating the usual expert service, and insuring that the tile when laid will be firmly fixed in the base on which they are laid and accurately and relatively disposed to provide a proper tile surface.

In the tile described in the said application, two adjacent edges of the tile are formed as recessed edges, while the remaining adjacent edges are formed to provide ledges shaped to interlock with the recessed edges of neighboring tile, the ledges being perforated for the reception of nails or like securing means. As conventionally constructed in the tile forming machine where the material is fed from the machine in a ribbon-like form of appropriate thickness and of proper tile width, the side edges of the ribbon are extruded to form proper tile edges during the formation of the ribbon, and as this ribbon is divided into tile lengths, it is, of course, apparent that each tile after transverse cutting of the ribbon will have two of its opposite edges properly formed and the remaining edges without formation. In order to complete the tile, therefore, means must be provided for properly forming the remaining edges, and as one of the edges already formed includes the ledge formation which is to be constructed for the reception of nails or the like, the completion of the tile must not only include the formation of the then unformed edges but also the perforation of the ledge forming edge extruded in the ribbon forming machines.

The primary object of the present invention, therefore, is the provision of means by which the unformed edges of the divided tile

may be properly and completely formed in a single operation, with such means also serving to perforate the ledge formation of one of the previously formed tile edges.

It is, of course, important that the edges of the completed tile be at right angles to each other and also that the movement of the forming implements of the present invention be such as to cut a true straight formation on the tile edge, and in order to secure these results it is desirable that the edge of the tile to be cut be held in a vertical plane and that the already formed edge be held at a right angle to the plane of movement of the forming implement of the present invention.

Therefore, the present invention contemplates a vertically moving forming implement and means by which the tile may be held through the medium of one of its already formed edges so that such formed edge is at direct right angles to the plane of movement of the forming implement of the present invention.

As successive tiles subjected to the action of the forming instrument of the present invention are similarly formed, that is, identical edges of successive tiles are given identical formation, it is apparent that the tiles may, for the purpose of the operation of the present forming apparatus, be held in pairs in order that two tiles, that is, the unformed opposite edges of two tiles, may be acted on by the forming apparatus of the present invention in a single operation. In Patent #1,770,406, issued to me July 15, 1930, I have described and claimed a tile handling apparatus, in which tile delivered from a tile making machine are positioned in pairs in vertical plane, with their wearing faces in contact in order to protect these faces during the subsequent handling of the tile in drying and burning, and as the patented apparatus in thus positioning the tile to protect these wearing faces arranges such tile in vertical position, that is, in a position most convenient for the operation of the tile forming apparatus of the present invention, such patented structure is utilized as part of the present invention for the purpose of accurately posi-

tioning the tile for the operation of the tile edge forming devices.

Generally speaking, therefore, the present invention is directed to means for arranging two tile as delivered from the extruding machines, with two of their edges already formed into vertical contacting relation, with their wear faces adjacent and thus protected and with their unformed edges in position to receive edge forming implements moving vertically, with which implements are associated means for perforating one of the edges so formed and also means for perforating one of the edges formed in the extruding machine, so that the tile as delivered from the extruding machine and after severing into tile lengths may be completed as to their edge formation while arranged in pairs to protect their wear faces and subsequently handled in pairs during the drying and burning operations.

The invention is illustrated in the accompanying drawings, wherein:—

Figure 1 is a side elevation of the improved tile edge forming apparatus.

Figure 2 is a front elevation of the same, being shown in duplicate to simultaneously form the edges of four tile.

Figure 3 is an enlarged sectional view of one of the perforating implements.

Figure 4 is a section on the line 4—4 of Figure 3.

Figure 5 is a sectional view illustrating particularly the mounting for the edge forming implements.

Figure 6 is an edge view of the same.

Figure 7 is a view in elevation similar to Figure 5, illustrating particularly the location of the perforating implements.

Figure 8 is an elevation viewed from the inner side of one of the edge forming implements and illustrating particularly the relation of the perforating implements.

Figure 9 is an enlarged vertical section showing the means for operating the edge forming implements.

Figure 10 is a section on the line 10—10 of Figure 9.

Figure 11 is a bottom plan view of the bushing and coupling for guiding the square spindle of the apparatus.

Figure 12 is an enlarged plan view of the handling machine in which the tile are arranged in position for the edge forming operation, the parts being shown in inoperative relation.

Figure 13 is an edge view, partly in section, of the same, the tile handling platen being shown in operative position, with the tile therebetween in relation to permit the edge forming operation.

Figure 14 is a perspective view of a tile, two of the opposite edges of which are formed in the present edge forming apparatus.

The present invention is directed to com-

pleting the edge formation and properly perforating the edges of a tile such, for example, as illustrated in Figure 14. As indicated in this view, the tile 1 has two adjacent edges, as 2 and 3, formed of peculiar recessed formation, the remaining edges 4 and 5 being formed to present ledges 6. The ledges 6 are designed to interfit with the recessed edges of adjacent tile, and such ledges are further formed with openings 7 through which nails or like fastening means are driven into a supporting surface for nailing the tile in place. In the extruding machine, two opposite edges of the tile will be formed in the formation of the ribbon as, for example, 3 and 4, but in the dividing of the ribbon into tile lengths, the edges 2 and 5 will be square, unformed edges and also the ledge formation 4 formed in the extruding machine will not be perforated for the reception of the securing nails. The present invention is designed to properly complete these unformed edges and provide for the perforating of the edge 4 previously formed in the extruding machine.

While the present invention is illustrated and will be described more particularly in connection with a tile having the edge formation shown and above referred to, it is understood that through a mere change of forming members, any desired edge formation may be given to the tile, and the invention is to be understood as in no wise limited by the specific description and illustration with reference to a particular edge formation.

As previously stated, Patent No. 1,770,406 issued to me July 15, 1930, describes and claims a tile handling apparatus which, with the addition of certain characteristics peculiar to the present invention, is made use of as a desirable and important adjunct to the edge forming apparatus, such tile handling apparatus being briefly described as follows:—

The tile handling apparatus as illustrated more particularly in Figures 12 and 13 includes an appropriate supporting frame 8 comprising side bars 9 adjustably mounted with relation to an intermediate bar 10 to provide for endwise adjustment of the side bars. The side bars carry shafts 11 arranged in spaced parallel relation and capable, through adjustment of the side bars, of being spaced different distances apart to accommodate tile of different thicknesses.

Swingingly supported on each shaft 11 through brackets 12 are pallets 13 having a smooth, even, upper surface to receive and support the tile. Also supported on the shafts 11 are end gauge plates 14. These end gauge plates are designed to receive and gauge the tile when the latter are laid on the pallets and also support the tile when the pallets are turned into vertical position to arrange such tile in position to provide for the operation

of the edge forming apparatus. The end gauge plates 14 are arranged to be operated in the positioning movement of the pallets 13, for which purpose the inner edges of the pallets are designed to bear against the lower portions of the gauge plates above their mounting on the shafts 11, as indicated at 16, so that as the pallets are moved to vertical position, indicated in dotted lines in Figure 13, the gauge plates will be compelled to follow such movement, though, through the independent mounting of the gauge plates relative to the pallets, the gauge plates may remain in operative position when the pallets are returned to normal or inoperative position.

The pallets and gauge plates are moved to operative position through the medium of arms 17 connected to the respective pallets and actuated in opposite directions in any simple or preferred manner, and limited in the operative movement to hold the tile in upright contacting relation without undue pressure through rods 18 carried by the pallets and guided through eyes 19 with an adjustable limiting means 20 on the rods to insure accurate positioning of the pallets. To permit the pallets to return to normal position, while insuring that the end gauge plates will remain in tile supporting position, the latter are provided with arms 21 which, as described in the patent, are connected to weights over suitable pulley supports to hold the end gauge plates in the position indicated in dotted lines in Figure 13, while permitting the return of the pallets to the normal positions or those positions indicated in full lines in such figure.

For the purposes of the present invention, the end gauge plates which, when the parts are in normal position, are arranged at the inner edges of the respective pallets and project at right angles and above the receiving surfaces of such pallets, have a formation complementary to the edge formation of one of the edges of the tiles. Thus the end gauge plates are formed on their operative surfaces to accurately receive the recessed edges, either two or three as the case may be, of the tile, such surface formation of the end gauges being indicated at 22 and the tile edges to cooperate therewith being the recessed edges of the tile formed by the extruding machine.

As is understood in tile forming machines, the tile in proper sizes, and for the present invention with two opposing edges formed in the extruding machine, are carried on the off bearing belt, not shown, and two of such tile are arranged in the handling machine described, being manually taken from the belt and placed on the respective platen, with their formed edges, as 2, accurately inter-fitted with the formed surfaces of the end gauge plates 14. The mechanism control-

ling the arms 17 is then operated and the platen and end gauge plates swung on the shafts 11 until the platen are in vertical, spaced, parallel relation with the tile carried thereon in contact, with such tile supported on the respective gauge plates 14 which are now in horizontal position in edge contact with their formed surfaces uppermost, all as clearly shown in Figure 13 of the drawings.

In this position, the upper and lower edges of the tile are those edges which have been previously formed in the extruding machine, while the side edges are the unformed edges resulting from the operation of the cutting wire in dividing the ribbon into tile lengths. As understood from the patent referred to, the contacting surfaces of the tile are the uppermost or wear surfaces, so that during the operation of the edge forming apparatus to be described, these surfaces are protected against marring and are further protected during the subsequent handling of the tile in drying and burning, as set forth in the description of the patent referred to.

The edge forming apparatus of the present invention includes as an element guiding means for cooperating with the platen, and for the purpose of insuring initial cooperation of the guiding means each platen is centrally formed with a projection 23 which extends materially above the upper edges of the tile when in position in the tile handling apparatus to permit the cooperation of the edge forming apparatus.

For economy in operation, it is understood that the tile handling apparatus is duplicated on opposite sides of the off bearing belt at a plurality of stages throughout the length of the belt so that all tile carried on the belt may be properly handled and that the edge forming apparatus is duplicated and designed for simultaneous operation at each duplicated tile handling station. This is illustrated more particularly in Figure 2, where it will be seen that by reason of the arrangement, four tile are simultaneously handled at each tile handling station and the edges of the four tile are completed through the single operation of a duplicated edge forming apparatus. Of course, for the purposes of the present description, a detailed explanation of one of such edge forming apparatus will be sufficient.

The edge forming apparatus comprises a supporting frame 24 of skeleton form, from the upper cross bar of which is supported a cylinder 25. The cylinder 25 has a removable dome section 26 formed at 27 for the admission of air under pressure, which dome section is connected to a tubular hanger 28 supported in a bracket 29 connected to the cross frame bar and adjustable therein by upper and lower nuts 30. The tubular hanger is open at the upper end for free exhaust purposes.

The lower end of the cylinder 25 is provided with a union 29 within which is threaded an annular, interiorly threaded abutment 30, and threaded within the abutment is a 5 guide sleeve 31. A piston 32 is operative within the cylinder 25 having the usual sealing cup washer 33, and secured to the lower surface of the piston is an annular block 34 designed, when the piston is in fully lowered 10 position, to engage the flexible washer 35 resting upon the upper edge of the abutment 30 and guide sleeve 31, to thus absorb the shock of operation. The block 34 is interiorly threaded to receive what may be termed a 15 hollow shaft 36, and threaded into the lower open end of this hollow shaft is the circular head 37 of a guide shaft, which below the circular head is diametrically reduced and of angular form, preferably square in cross section, as at 38. As the shafts 36 and 38 are 20 moved vertically in the operation of the piston, and as the edge forming implements are carried by the shaft 38, it is, of course, of importance that this shaft be accurately guided in vertical movement and prevented from 25 possibility of turning during such movement, as otherwise the edges of the tile would be improperly or imperfectly formed.

To provide for the more effective, accurate 30 guiding of the shaft 38 particularly, the latter is arranged to pass through a bushing 39 threaded into the lower end of a coupling 40 secured on the exterior of the guide sleeve 31. The bushing is formed with an opening accurately conforming in size and shape to that 35 of the section 38 of the shaft, and both the bushing and union 40 are vertically divided for a portion of their lengths, with the divided portions of the union provided with 40 ears 41 connected by tightening means 42, such as bolts and nuts, whereby any play in the bushing relative to the portion 38 of the shaft may be taken up and the shaft accurately and positively guided in the desired line.

45 A transverse arm 43 underlies the extreme lower end of the shaft section 38, being secured thereto by a bolt 44 threaded into the lower end of the shaft. A positioning ring 45 accurately fitting the exterior and conforming to the shape of the section 38 of the shaft immediately overlies and is secured to the arm 43 by bolts 46. Thus the arm is held rigidly with respect to the shaft 38 and prevented from any displacement relative thereto in any direction. The transverse arm 43 is formed on each side of the shaft 38 with elongated apertures 47 to provide for adjustment of the forming implements relative to each other.

60 Secured to the under side of the arm 43 and depending in spaced, parallel relation therefrom are guide fingers 48 which depend in such spaced relation that their inner surfaces accurately cooperate with the outer surfaces of the platen 13 in line with the projec-

tions 23 when the forming apparatus is moved downwardly and the platen with the enclosed tile are in the position illustrated in dotted lines in Figure 13. If desired, the lower ends of the guide fingers may be gradually reduced in width in side elevation and tapered on their inner surfaces to insure more accurate registry with the platen, such formations being illustrated in Figures 5 and 6.

The elements for cutting the edges of the tile are, of course, to be constructed to form such edges of the desired outline, the cutting blade of each element being so formed as to properly outline the edge of the two adjacent tile as held between the platen in a single operation. As these cutting elements in the particular use to which they are here assigned are designed to form different shapes of edges, one will be hereinafter termed the recess forming element which is designed to form the recessed edges of the tiles, and the other will be hereinafter termed the ledge forming element which is designed to form those edges of the tiles carrying the ledges.

The recess forming element includes a bar 49 threaded at the upper end, as at 50, with the threaded end designed to be extended through one of the slots 47 of the arm 43 and secured thereto in rigid adjusted position lengthwise the slot by disks 51 which bridge the slot from above and below, and nuts 52 which cooperate with the threaded portion 50 of the element to rigidly secure the element in place. The lower end of the element is inwardly deflected toward the fingers 48 and is terminally provided with a cutting blade 53 which is shaped in its movement vertically of the edges of the tile to form the recessed edge formation of the two related tile, such edge formation being a duplicate of that shown in dotted lines at the lower end of the tile in Figure 13.

The offset formation of the rod 49 serves to prevent possible contact with such rod above the cutter with the material of the tile. The ledge forming element includes a bar 54 threaded throughout its upper portion at 55 for cooperation with the opposite, elongated opening 47 in the arm 43, disks 56 and nuts 57 insuring a rigid connection between the rod 54 and the arm 55 in any adjusted position of said rod in the elongated opening 47 of the arm. The lower end of the rod 54 is provided with a cutting blade 58 which is shaped to form the edges of the tile opposite those edges formed by the cutter 53 to provide the ledge formation. The cutter 58 is formed to shape the edges of both tile with which it cooperates to form such edges substantially of the shape shown at the upper portion of the dotted tile outline in Figure 13, it being noted from this figure that the cutter forms the ledges 6 in line with the outermost surfaces of the tile so that the tile together

present a vertical channel 59 between the ledges 6, as shown in Figure 13.

In connection with the particular tile being formed by this apparatus, the forming element 54 forms the ledges 6 on the similar edge of both tile, the right angled edge of each of such tile having been previously formed with a corresponding ledge 6 in the original formation of the tile ribbon, as previously described. These ledges 6, however, both those originally formed and those formed by the apparatus of this invention, require to be perforated for the formation of the nail-receiving openings 7 therein. A salient and important detail of the present invention resides in the means whereby these nail-receiving openings 7 are formed, both in the ledges 6 formed by the apparatus itself and in the ledges 6 previously formed by the initial ribbon forming machine.

For the formation of the nail-receiving openings 7 in the ledges resulting from the operation of the ledge-forming implement 54, such implement immediately above the forming blade 58 is shaped to accurately fit in the channel 59 between opposing ledges 6, this shaped portion of the ledge-forming element being of elongated, block-like form, as at 60. This block-like body 60 is transversely bored to provide openings 61 opening through both sides of the block on spaced, parallel, relatively inclined lines, and similar openings 62 opening through both sides of the block on spaced parallel lines reversely inclined with respect to the lines of the openings 61. The outlet ends of each set of openings 61 and 62 are on opposite sides of the block respectively, that is, assuming the channel 59 in Figure 13 to be the channel through which the body or block 60 is moved, the outlet ends of one set of openings, as 61, will be next the relatively inner surface, as appearing in such figure, of one of the ledges 6, while the outlet ends of the other openings 62 will be similarly placed with respect to the opposite ledge 6. The entrance ends of the respective openings 61 and 62 are disposed outwardly beyond the plane of the edge of the tile, and these outlet ends are diametrically enlarged and interiorly threaded to receive nipples 63 projecting from a cylinder 64 in which a piston 65 is operative.

The piston carries a rod 66 which extends through the nipple 63, and under appropriate operative movement of the piston through the outlet end of the particular opening 61 or 62, as the case may be, and in this movement serving to pierce the particular ledge 6 with which it cooperates for the formation of the nail-receiving holes 7 therein. As stated, the openings 61 and 62 incline downwardly from their entrant and their exit ends, and the cylinders 64 are secured at the entrant end of the respective openings so that the piston rods 66 will simultaneously, when

all cylinders are served, pierce the respective ledges 6 in the proper position and at the proper inclination.

The upper ends of the cylinders 64 are provided with a removable cap 67 having a communicating nipple 68 arranged for the reception of a pipe for supplying air under pressure, as will later appear, a spring 69 being coiled about the rods 66 between the piston and lower wall of the cylinder to return the piston and thereby the piercing rods 66 to normal or inoperative position upon the relief of the pressure. The cylinder near its lower end is formed with outlet openings 70 to permit the escape of air below the piston in the operative movement of the piston.

In addition to piercing the formed ledges 6 with a nail-receiving opening 7, it is also necessary to similarly pierce the ledges 6 of those tile edges which were formed in the ribbon forming machine, as previously explained, and which, of course, are disposed at right angles to the ledges formed by the apparatus of this invention. To secure this result, a block-like bar 71 is secured through the medium of a threaded bolt 72 to the lower end of the non-circular shaft 38, the bolt 72 being preferably threaded into the bolt 44 serving to secure the arm 43 to said shaft 38. Lock nuts 73 are provided for rigidly maintaining the position of the block 71. The block 71 is disposed at right angles to the plane of the block 60 and in such relation to such block 60 that when the block 60 is in position to form the openings 7 in the ledges 6 provided as a result of the operation of the blade 58, the bar 71 will be resting in the opening between the ledges 6 which have already been formed in the ribbon forming machine in the initial formation of the tile material. The block 71 is formed with two sets of openings 74 and 75 of opposite inclination, with their exit ends adjacent the inner surfaces of the respective ledges of the tile and their entrant ends formed for the reception of cylinders 64 similar to that described in connection with the block 60 and illustrated specifically in Figure 3 of the drawings.

Thus, after the machine has operated the nail-receiving openings of the ledges formed by the machine and those previously formed in the formation of the tile ribbon may be simultaneously pierced to provide the openings 7, with such openings in proper relation and at proper inclination to complete this detail of the tile in accordance with the description in the application previously referred to.

As previously stated the tile edge forming apparatus of this invention is arranged in pairs on opposite sides of the off bearing belt, with any desired duplication of such pair of tile edge forming machines arranged

in succession longitudinally of the belt as may be necessary to take care of the volume of tile being produced. The arrangement in pairs at any one station is simply for convenience and economy in manufacture, permitting convenient handling of the tile and operation of the edge forming apparatus. The edge forming movement of the apparatus is, of course, resultant from the operation of the piston 32, and to secure this operation a pipe line 76 open to a source of air under pressure is arranged to serve any and all edge forming apparatus. This pipe line has a by-pass 77 leading to the cylinder 25 through the opening 27, the by-pass being provided with a manually controlled valve 78 for the control of the operation of the piston 32 at will. The by-pass 77 is provided before the valve 78 with a lateral pipe extension 79 carrying a manually operable valve 80 and beyond the valve connected by flexible piping 81 to the nipples 68 of what may be termed the piercing cylinders 64.

To return the pistons 32 to normal or inoperative position, a cross bar 82 is passed with a driving fit through diametrically opposed slots 83 in the hollow shaft 36 and extends through slots 84 in the guide sleeve 31, the latter slots being of sufficient length to permit a fully operative movement of the hollow shaft 36. The ends of the bar 82 are connected by cables 85 with weights 86, the cables passing over pulleys 87 supported from the upper cross bar of the frame 24, as shown in Figure 2, the cables 85 on each side of each apparatus of the pair being led over the same pulley. Of course, it is understood that the valves 80 controlling the piercing cylinders are provided with an exhaust outlet 88, so that upon closing the valve 80, the cylinders are open to the exhaust, whereupon the springs 69 operate to return the pistons 65 to inoperative position and withdraw the piercing rods 66.

In the operation of the improved mechanism, the operator having charge of a particular edge forming machine or machines will pick up off of the off bearing belt two tile in succession and dispose them on the platen 13 of the handling machine, which platen are in the position illustrated in full lines in Figure 13. In this position, the end gauge plates 14 are in the position illustrated in full lines in said Figure 13, and in placing the respective tile on the platen, care is taken to register the already formed recessed edges in two of the tile accurately with these gauge members 14. The arms 19 are now operated to turn the platen 13 into the position shown in dotted lines in Figure 13, this movement of the platen turning the edge gauges 14 into horizontal position so that when the parts are in this relation the tile on the respective platen are in contact between the platen, with their recessed formed edges in engagement

with and supported by the end gauges 14 and their ledge formed edges uppermost. The tile are disposed on the platen longitudinally so that their wear or upper surfaces, when laid, are uppermost so that when turned into the position shown in dotted lines in Figure 13, these wear faces of the respective tile are in contact and are thus protected against being marred, broken or otherwise interfered with during the operations to which the tile may be subsequently subjected.

When the tile are arranged in this position in the tile handling apparatus, the edges of the adjacent tile held between the upright platen 13 are, of course, unformed. The valve 78 is operated and air admitted to depress the piston 32 of the edge forming apparatus. If an operator is handling two edge forming apparatus, the tile may be positioned in the respective handling apparatus and two edge forming apparatus operated through a single control valve or through the operation of two such control valves, as may be desired. Under pressure of air, the piston 32 descends, carrying with it the shaft 38, which, as stated, is of non-circular form, and by reason of the guiding functions of the cooperating parts held against possibility of turning.

As the edge forming apparatus moves downwardly, the ends of the fingers 48 engage the outer surfaces of the projections 23 of the platen and thereby absolutely center and positively guide the forming elements in correct relation to the edges of the tile to be formed thereby. In the continued downward movement of the shaft 38, the forming blades 53 and 58 form the respective edges of the two adjacent tile to cause these edges to correspond one with the recessed edge 2 and the other with the ledge edge 4. As the blades 53 and 58 reach their downward limit, that is, the lower end of the tile edges, the bar 60 is positioned between the ledges of the edges just formed, while the bar 71 is positioned between the ledges of the tile edges previously formed. The valve 80 is then opened and air under pressure admitted to the respective piercing cylinders 64, whereupon the pistons 65 are depressed against tension of the springs 69 and the piercing rods 66 form holes at the appropriate places and at the appropriate angles in the ledges, both those previously formed and those formed by the cutting blade 58. Upon closing of the valve 80, the cylinders 64 are opened to an exhaust and the springs 68 operate to return the piercing rods to the normal or inoperative position free of any possibility of interference from the tile material, whereupon the valve 78 is closed, permitting the cylinder 25 to exhaust to the atmosphere and the weights 86 to return the piston and edge formers to normal or inoperative position. The arms 17 of the handling apparatus are then actuated in the opposite directions, which return the platen

13 to their normal or inoperative positions, leaving the formed tile in contact resting upon and supported by the edge gauges 14 of the respective platen. The two tile thus completed as to edge formation with their wear surfaces in contact are subsequently handled as a unit, being manually transferred to the belt or other conveyor to be carried away for drying and subsequent burning to complete 10 the tile formation.

It is, of course, to be understood that any edge formation desired for the tile may be completed in the present machine, the same only requiring a proper configuration of the 15 blade elements 53 and 58 and, if necessary, the arrangement of the means for piercing the nail-receiving openings in proper relation to the blade-forming elements. Obviously, tile of different thickness may be readily accommodated by the adjustment of the forming 20 elements through the medium of the elongated openings 47 formed in the arm 43.

An essential and characteristic feature of the invention is in the combination of the 25 tile handling machine in which two tile are arranged to protect their wear faces and positioned so that their unformed edges may be simultaneously formed in a single operation, and in the consideration of this combination 30 it is to be understood that no restriction as to the particular form of the tile handling apparatus or as to the particular form of the edge forming mechanism is to be inferred from the specific illustration and description 35 herein, it being contemplated that appropriate means for the operation and positioning of the platen and appropriate means for operating the edge forming and shaping implements to attain the results herein particularly specified which may structurally vary 40 in considerable degree to that specifically described is within the spirit of the present invention.

I claim:—

45 1. In combination, tile handling apparatus for positioning and supporting a plurality of tile in a predetermined relation, and edge forming means for particularly forming similar edges of all said tile while in the 50 tile handling apparatus.

2. In combination, tile handling apparatus operating to position and support two tile with their wear faces in contact, and edge forming apparatus operating to particularly 55 form opposing similar edges of both said tile in a single operation while the tile is in position in the tile handling apparatus.

3. In combination, tile handling apparatus including means to receive, position and support two tile with their wear faces in contact, and edge forming apparatus including means to cooperate with the opposing similar edges of both of said tile simultaneously, and particularly form such edges.

60 4. In combination, tile handling appara-

tus including means to receive, position and support two tile with their wear faces in contact, and edge forming apparatus including means to cooperate with the opposing similar edges of both of said tile simultaneously, and particularly and distinctively form such edges.

5. In combination, tile handling apparatus including means to receive, position and support two tile with their wear faces in contact, and edge forming apparatus including means to cooperate with the opposing similar edges of both of said tile simultaneously, and particularly and distinctively form such edges, said edge forming apparatus including means for the piercing of certain portions of the formed edges of the tile to provide nail-receiving openings therein.

6. In combination, a tile handling apparatus for receiving, positioning, and supporting two tile with their wear faces in contact and with their opposed edges particularly formed in the extruding apparatus, the tile handling apparatus including means to register with certain of the formed edges in the tile for accurately maintaining the tile position in said handling apparatus, and means whereby the remaining edges of the tile may be formed while the tile remains in the tile handling apparatus.

7. In combination, a tile handling apparatus for receiving, positioning and supporting two tile with their wear faces in contact and with their opposed edges particularly formed in the extruding apparatus, the tile handling apparatus including means to register with certain of the formed edges in the tile for accurately maintaining the tile position in said handling apparatus, and means whereby the remaining edges of the tile may be formed while the tile remains in the tile handling apparatus, said edge forming means including mechanism for piercing predetermined portions of the edges so formed.

8. In combination, a tile handling apparatus for receiving, positioning and supporting two tile with their wear faces in contact and with their opposed edges particularly formed in the extruding apparatus, the tile handling apparatus including means to register with certain of the formed edges in the tile for accurately maintaining the tile position in said handling apparatus, and means whereby the remaining edges of the tile may be formed while the tile remains in the tile handling apparatus, said edge forming means including mechanism for piercing predetermined portions of the edges so formed, said edge forming mechanism also including means for piercing certain portions of those edges of the tile formed prior to the introduction of the tile in the handling apparatus.

9. An apparatus for particularly forming the edge of a tile including an appropriately shaped blade, means for forcing the blade

- lengthwise the tile edge to shape said edge in accordance with the form of the blade, and means for piercing a predetermined portion of the formed edge.
- 5 10. An apparatus for particularly forming the edge of a tile consisting in an edge forming element, means for moving the element longitudinally of the edge, a forming blade carried by the element to shape the edge, a 50
10 block carried by the element and positioned in predetermined relation to the formed edge following the formation of the edge, and piercing means carried by the block.
- 15 11. A tile edge forming apparatus for simultaneously forming the similar edges of two tile with their wear surfaces in contact and in registry comprising an element movable lengthwise the two tile edges to be formed, a blade carried by the element to 55
20 simultaneously and similarly form both said edges, a block carried by the element to be arranged in a predetermined position between the formed edges following their formation, and piercing elements carried by the 60
25 block to operate on both formed edges respectively in a single operation.
12. A tile edge forming apparatus for the forming of the opposed edges of a plurality of tile, the remaining edges of which have 65
30 been previously formed, including forming elements movable longitudinally of the similar edges of two tile, blades carried by the elements to simultaneously form such similar edges, piercing members carried by one 70
35 of the elements for piercing one of the formed edges, and a piercing mechanism movable with the elements for simultaneously piercing one of the previously formed edges of the tile.
- 40 13. A tile edge forming apparatus including an arm, tile forming elements adjustable longitudinally of the arm, forming blades carried by the elements, piercing mechanism carried by one of the elements, means responsive to air pressure for moving the arm, and means responsive to air pressure for operating the piercing mechanism.
- 45 14. A tile edge forming apparatus including an arm, tile forming elements adjustable longitudinally of the arm, forming blades carried by the elements, piercing mechanism carried by one of the elements, means responsive to air pressure for moving the arm, means responsive to air pressure for operating the piercing mechanism, and an additional piercing mechanism supported by the arm for cooperation with edges of the tile other than the edges formed by the blades.
- 55 15. A tile edge forming apparatus including an arm, tile forming elements adjustable longitudinally of the arm, forming blades carried by the elements, piercing mechanism carried by one of the elements, means responsive to air pressure for moving the arm, 125
60 means responsive to air pressure for
- operating the piercing mechanism, an additional piercing mechanism supported by the arm for cooperation with edges of the tile other than the edges formed by the blades, said latter piercing mechanism being responsive to air under pressure, and means for independently controlling the movement of the arm in the operation of the piercing mechanisms.
- 65 16. A tile edge forming element including a bar, means for reciprocating the bar with respect to the edge of the tile, a blade carried by the lower end of the bar, said bar being formed above the blade with lateral openings, and piercing elements carried by the bar and operative through said openings.
- 70 17. A tile edge forming element including a bar, means for reciprocating the bar with respect to the edge of the tile, a blade carried by the lower end of the bar, said bar being formed above the blade with lateral openings, piercing elements carried by the bar and operative through said openings, and manually controlled means for governing the admission of air under pressure to and for the operation of the piercing elements.
- 75 18. A tile edge forming apparatus including a non-circular shaft adapted for reciprocation and held against rotation, means for reciprocating the shaft, an arm carried by the shaft, tile edge forming elements adjustable in said arm, blades carried by the lower end of the elements for cooperation with and particularly forming the edges of a tile, piercing elements responsive to fluid pressure and carried by and positioned with respect to the tile in the movement of the edge forming element, and means for selectively controlling the movement of the shaft in the operation of the piercing elements.
- 80 19. A tile edge forming apparatus including a non-circular shaft adapted for reciprocation and held against rotation, means for reciprocating the shaft, an arm carried by the shaft, tile edge forming elements adjustable in said arm, blades carried by the lower end of the elements for cooperation with and particularly forming the edges of a tile, piercing elements responsive to fluid pressure and carried by and positioned with respect to the tile in the movement of the edge forming element, means for selectively controlling the movement of the shaft in the operation of the piercing elements, and means for returning the bar and piercing elements to normal position following the relief of the fluid pressure.
- 85 20. In combination, a tile handling apparatus for positioning and supporting a plurality of tile in predetermined relation, and means for simultaneously and particularly forming opposing similar edges of such plurality of tile.
- 90 21. In combination, a tile handling apparatus for maintaining a plurality of tile in

contact and supported on similar edges, and means for particularly forming the parallel edges of supported tile above the supporting edge of such tile.

5 22. In combination, a handling apparatus to receive and support a tile having two of its edges previously particularly formed and the remaining two edges unformed, said handling apparatus supporting the tile on one of 10 the formed edges, and means cooperating with the unformed edges of the tile to form such edges in a particular outline.

23. In combination, a handling apparatus designed to receive and position a tile having two opposing edges particularly and differently formed, with the remaining edges unformed, said handling apparatus supporting a tile on one of the formed edges, and means cooperating with the tile to simultaneously and particularly form the unformed edges of the tile in respective accordance with the previously formed edges.

24. In combination, a tile handling apparatus including means to receive, position 25 and support two tile in contact and on an edge, and selectively operable mechanism for shaping two of the edges other than the edge on which the tile is supported while the tile are in the handling apparatus.

30 25. In combination, tile handling apparatus including means to support two tile on edge with their wear faces in contact, and edge forming apparatus including means to cooperate with the opposing similar edges of both of said tile simultaneously, and particularly form such edges.

26. In combination, tile handling apparatus including means to receive, position and support two tile on edge with their wear 40 faces in contact, and edge forming apparatus including means to cooperate with the edges of both of said tile simultaneously, and particularly and distinctively form such edges.

27. In combination, tile handling apparatus including means to receive, position and support two tile with their wear faces in contact, and edge forming apparatus including means to cooperate with the opposing similar edges of both of said tile simultaneously, and 50 particularly and distinctively form such edges, said edge forming apparatus including additional means for operating on certain portions of the formed edges.

55 28. In combination, a tile handling apparatus for receiving, positioning and supporting two tile with their wear faces in contact and with their opposed edges particularly formed in the extruding apparatus, the tile 60 handling apparatus including means to register with certain of the formed edges in the tile for accurately maintaining the tile position in said handling apparatus, and means whereby the remaining edges of the tile may 65 be formed in respective accordance with the

previously formed edges while the tile remains in the tile handling apparatus.

29. In combination with a tile having two opposing edges particularly formed and the remaining opposing edges plain, of means for supporting the tile on one of its formed edges, and means for cooperating with the plain edges of the tile while so supported for forming such plain edges in respective correspondence with the previously formed edges.

In testimony whereof I affix my signature.
VICTOR J. HULTQUIST. [L. s.]
